(57) **CLAIM**

The ornamental design for a handrail bracket, as shown and described.

DESCRIPTION

FIG. 1 is an isometric view of a handrail bracket of our new design in an installed environment.

FIG. 2 is an enlarged isometric view of the handrail bracket of FIG. 1.

FIG. 3 is a front elevational view thereof.

FIG. 4 is a back elevational view thereof.

FIG. 5 is a left side elevational view thereof, the right side elevational view is a mirror image of the left side.

FIG. 6 is a bottom plan view thereof; and,

FIG. 7 is a top plan view thereof.

Shading lines shown in the drawings are intended to represent the three-dimensional contour of the design, and are not intended to indicate surface decoration. The broken lines in FIGS. 1, 2, 4, 6, and 7 depict environmental subject matter only and form no part of the claimed design. Unshaded surfaces form no part of the claim.
